United States Patent Office.

NICHOLAS MÜLLER, OF NEW YORK, N. Y.

Design No. 4,187, dated June 28, 1870.

DESIGN FOR A STATUETTE.

The Schedule referred to in these Letters Patent and making part of the same

To all whom it may concern :

Be it known that I, NICHOLAS MÜLLER, of the city, county, and State of New York, have invented a new and ornamental Design for a Statuette; and I do hereby declare that the following is a full, clear, and exact description thereof, which will enable those skilled in the art to make and use the same, reference being had to the accompanying photograph forming part of this specification, in which the design is represented by a front view.

This invention relates to a design for a statuette representing a young Indian warrior in the act of throwing his tomahawk. His back and loins are covered with a pauther's skin, held together by a strap, which lies diagonally across his chest. His right foot is advanced, both feet being covered with moccasins; his

left hand grasps a bow, one end resting on the ground, on which he slightly leans; in his right hand, which is raised, he holds a tomahawk over his head, just about to fling it; his head is ornamented with feathers, tied with a band. The whole figure stands on a suitable base, as may be seen in the photograph.

What I claim as my invention, and desire to secure by Letters Patent, is—

The design for a statuette, as herein shown and described.

Signed this 25th day of May, 1870.

NICHOLAS MÜLLER.
